[57] CLAIM

The ornamental design for a mixer with base stand, as shown and described.

DESCRIPTION

FIG. 1 is a front perspective view of a mixer with base stand showing my new design;

FIG. 2 is a front perspective view of the mixer shown in FIG. 1 shown separately for ease of illustration;

FIG. 3 is a front elevational view of the mixer of FIG. 2;

FIG. 4 is a right side elevational view of the mixer of FIG. 2 which is also an identical mirror-image of the left side of the mixer;

FIG. 5 is a rear elevational view of the mirror of FIG. 2;

FIG. 6 is a top plan view of the mixer of FIG. 2;

FIG. 7 is a bottom plan view of the mixer of FIG. 2;

FIG. 8 is a front perspective view of the base stand shown in FIG. 1 shown separately for ease of illustration;

FIG. 9 is a top plan view of the base stand of FIG. 8;

FIG. 10 is a front elevational view of the base stand of FIG. 8;

FIG. 11 is a rear elevational view of the base stand of FIG. 8;

FIG. 12 is a bottom plan view of the base stand of FIG. 8;

FIG. 13 is a left side elevational view of the base stand of FIG. 8; and,

FIG. 14 is a right side elevational view of the base stand of FIG. 8.
